DESIGN FOR A FIRE EXTINGUISHER

Daniel Mapes, West Caldwell, N. J., assignor to
Specialties Development Corporation, Belleville,
N. J., a corporation of New Jersey

Application November 14, 1947, Serial No. 142,540

Term of patent 14 years

(Cl. D16—2)

To all whom it may concern:

Be it known that I, Daniel Mapes, a citizen of the United States, residing in West Caldwell, in the county of Essex, in the State of New Jersey, have invented a new, original, and ornamental Design for a Fire Extinguisher, of which the following is a specification, reference being had to the accompanying drawing, forming a part thereof.

Figure 1 is an elevational view of a fire extinguisher, embodying my new design;

Figure 2 is a bottom plan view thereof; and
Figure 3 is a top plan view thereof.

The essential features of my design for the fire extinguisher disclosed reside in an elongated body and a nozzle portion at one end thereof having the configuration and arrangement as best shown in Fig. 1.

I claim:

The ornamental design for a fire extinguisher, substantially as shown and described.

DANIEL MAPES.
